(57) **CLAIM**

The ornamental design for a wall mount, as shown and described.

DESCRIPTION

FIG. 1 is a top, front, right perspective view of a wall mount showing my new design;

FIG. 2 is a front view thereof;

FIG. 3 is a top view thereof;

FIG. 4 is a bottom view thereof;

FIG. 5 is a right side view thereof; and,

FIG. 6 is a left side view thereof.

The broken lines immediately adjacent to the shaded area are directed to boundary lines, which form no part of the claimed design. The broken lines in the drawings are for the purpose of illustrating portions of the wall mount, which form no part of the claimed design.

1 Claim, 5 Drawing Sheets
